(57) **CLAIM**

The ornamental design for a fishing tackle box, as shown and described.

DESCRIPTION

FIG. 1 is a perspective view of a fishing tackle box. FIG. 2 is a front elevational view thereof, the rear elevational view being a mirror image of the front view.

FIG. 3 is a top plan view thereof.

FIG. 4 is a bottom plan view thereof.

FIG. 5 is a left side elevational view of the fishing tackle box; and,

FIG. 6 is a right side elevational view thereof.
